(57) **CLAIM**

The ornamental design for a cell analyzer as shown and described.

DESCRIPTION

1. Cell analyzer

1.1 : Front

1.2 : Back

1.3 : Left

1.4 : Right

1.5 : Top

1.6 : Bottom

1.7 : Perspective

The name of this design product: cell analyzer; purpose of the product with this design: for biological science detection and analysis; the main points of the design of the product are the shape of the product; the picture or photo that best shows the main points of the design: reproduction 1.7 (perspective view).

The broken lines indicate portions of the cell analyzer that form no part of the claimed design.
